US0D1055698S

(12) United States Design Patent (10) Patent No.: US D1,055,698 S
(45) Date of Patent: * Dec. 31, 2024

(54) BOTTLE

(71) Applicant: Medline Industries, LP, Northfield, IL (US)

(72) Inventors: Alyson Ovitt, Gurnee, IL (US); Kimberly Washington, Chicago, IL (US); Mark Krukonis, Libertyville, IL (US); Juniwati Katopo, Elgin, IL (US)

(73) Assignee: Medline Industries, LP, Northfield, IL (US)

() Term: 15 Years

(21) Appl. No.: 29/861,148

(22) Filed: Nov. 28, 2022

Related U.S. Application Data

(62) Division of application No. 29/712,471, filed on Nov. 8, 2019, now Pat. No. Des. 974,181.

(51) LOC (14) Cl. 09-01

(52) U.S. Cl. D9/558
USPC D9/558

(58) Field of Classification Search

USPC D9/500, 503-505, 516, 529-530, 537, D9/539-540, 549, 558, 574-575
CPC . B65D 1/02; B65D 1/0223; B65D 2501/0009
